ROWING DEVICE

Roy Lanning, Sabetha, and Clate Brougher,
Morrill, Kans.

Application May 23, 1947, Serial No. 750,060

1 Claim. (Cl. 9—25)

1

This invention relates to devices for manually forcing boats or the like through water and more specifically to an instrument for rowing in the form of a sectional oar.

The most important object of this invention is to provide a sectional oar designed to permit forcing a boat or the like through the water in the same direction in which the operator of the rowing instruments is facing.

Another important object of this invention is to provide a rowing instrument having an oar lock and an oar made from a handle section and a bladed section, each being pivotally mounted near one end thereof respectively to the oar lock and having a link interconnecting said ends to the end that as the handle section of the oar is moved in one direction, the bladed section thereof, swings in the same direction.

A further object of this invention is the provision of a rowing instrument having an oar lock and an oar formed from a handle section and a bladed section, each being pivotally connected to the oar lock near proximal ends thereof and having said proximal ends connected pivotally by a short link to the end that movement of the handle section on its pivot in one direction, swings the bladed section in the same direction on its particular pivot.

Other objects of this invention include the manner in which the pivotal connections between the oar lock and the oar sections are in spaced apart relation and substantially parallel; the way in which the sections of the oar, as well as the pivotal connecting link therebetween, all move on substantially the same plane when the rowing instrument is placed in use; and the way in which the oar lock per se is swingably supported by the boat when placed in use.

Many minor objects will be made clear or become apparent during the course of the specification, reference being had to the accompanying drawing, wherein:

Fig. 1 is a top plan view of a sectional oar made in accordance with our present invention.

Fig. 2 is a side elevational view thereof.

Fig. 3 is a cross-sectional view taken on line III—III of Fig. 2, looking in the direction of the arrows; and

Fig. 4 is a cross-sectional view taken on line IV—IV of Fig. 2, looking in the direction of the arrows.

It is common knowledge by any one who has ever rowed a boat by the conventional means, that when such operation takes place, the operator thereof travels in a direction opposite to that

2

which he is facing. This has many obvious disadvantages since the operator cannot readily see where he is going and disastrous results may occur in the form of accidents or other damaging effects. This has been harassing to many followers of this sport but heretofore, no satisfactory means has been provided to remedy the situation.

It is realized that oars have heretofore been made to make it possible to row a boat and face the direction of travel, but none of these instruments have been too satisfactory. Such conventional types of oars have been expensive to manufacture and when placed in use, have not provided the smooth action which is made possible by the sectional oar about to be described.

In the drawing, the numeral 10 designates broadly an oar lock which is formed to carry an oar designated by the numeral 12. The oar 12 is sectional, there being a handle section 14 and a bladed section 16. The bladed section 16 is provided with a blade or paddle 18 in the usual manner. The section 14 and the section 16 are each pivotally secured to the oar lock 10 as at 20 and 22 respectively.

25 The oar lock 10 constitutes a base plate 24 and an enclosed loop section 26. This section 26 has an inturned flange portion 28 and an out-turned flange portion 30, each of which is secured to the base plate 24 in any suitable manner such as by welding.

30 The looped section 26 has an uppermost wall 32 which is in spaced relationship to the base 24 and extends laterally from one end thereof in an elongated tongue 34. The pivotal bolts or the like 20 and 22 extend through the top plate 32 of section 26, thence through the respective sections 14 and 16 of oar 12 and then through the base plate 24, as clearly illustrated in Figs. 2, 3 and 4.

35 Suitable spacers 36 and 38 for bolts 20 and 22 respectively, maintain the sections 14 and 16 of oar 12 spaced from the upper and lowermost walls 32 and 24 of oar lock 10.

40 A pair of elongated plates 40 embraces the handle section 14 of the oar 12 at the end thereof adjacent to the oar lock 10 and extends laterally beyond this end of handle section 14, as clearly illustrated in Fig. 2, to pivotally receive one end of a second pair of elongated plates 42. The opposite end of these plates 42 extends laterally from the handle section 14 and embraces the innermost end of the section 16 of oar 12, as clearly shown in Figs. 3 and 4. The end of the plates 42 having connection with the handle section 14 is pivotally connected to the latter through the medium of a bolt or the like 44, while the opposite

end of the plates 42 has pivotal connection with the bladed section 16 of the oar 12 by a bolt or the like 46.

A barrel hinge for a substantially U-shaped member 48, is formed on the base plate 24 of the oar lock 10 by stamping a pair of tongues 50 therefrom, as clearly shown in Figs. 3 and 4. These tongues 50 are in spaced apart relationship and extend downwardly from the lowermost face of the base plate 24. The bight of this U-shaped member 48 is pivotally received by these barrel lips 50 to swingably support the oar lock 10 and the oar 12 supported thereby when the member 48 is mounted upon the boat. Any suitable means for receiving the two downturned legs of the member 48 may be provided in the boat. This receiving means in the boat (not shown) may simply constitute a pair of reinforced holes formed in the gunwale of the boat.

It is clear from the foregoing that when the oar lock 10 is mounted upon the boat through the medium of the U-shaped member 48 depending therefrom, the sectional oar may be placed in use and the operator thereof will face the direction of travel of the boat. When the handle section 14 of the oar 12 is grasped by the operator and pulled in a direction toward himself, the bladed section 16 will move in the same direction and will pull the boat through the water in the usual manner. This force which is exerted upon the handle section 14 of oar 12, will cause such swinging of bladed section 16 in the same direction by cause of the force imparted to the latter by the link 24 pivotally connecting the proximal ends of the sections 14 and 16.

It is clear from the foregoing that the purposes aforesaid are accomplished because of the spaced apart relationship between the bolts 20 and 22 pivotally mounting the sections 14 and 16 respectively to the oar lock 10. These bolts 20 and 22 are also in substantially parallel relationship and in substantial parallelism with the two pivotal connections 44 and 46 of the link 42. The bladed section 16, the handle section 14 and the link 42 will all travel in the same plane when the sectional oar is placed in use.

Manifestly, the sectional oar just described embodies but a few parts and it is, therefore, easily and inexpensively manufactured. Furthermore, the parts of this device will not easily get out of order as is true with the conventional type

of oar of this character having a plurality of complicated intermeshing gears to supplant the pivotal connections above described. When placed in use, this sectional oar operates extremely well and affords a smooth action to the boat and for the operator thereof.

While only one modification of our sectional oar has been illustrated and described, it is to be understood that many changes and modifications 10 may be made without departing from the spirit of this invention or scope of the appended claim.

Having thus described our invention, what is claimed as new and desired to be secured by Letters Patent is:

15. An instrument for rowing comprising an oar lock; an oar having a bladed section and a handle section; a pair of elongated plates rigidly secured to said handle section on opposed sides thereof and extending beyond one end of the handle 20 section, with the outer ends of the plates converging to a point of mutual contact; means pivotally mounting said plates and said handle section to the oar lock adjacent said one end of the handle section; means pivotally mounting 25 said bladed section near one end thereof to said oar lock; and a second pair of elongated plates, pivotally secured to said bladed section on opposed sides thereof at said one end of the bladed section and extending laterally from the latter 30 with the outer ends thereof converging and embracing the outer ends of said first mentioned plates, said outer ends of all plates being pivotally joined.
